UNITED STATES PATENT OFFICE.

ROBERT ALEXANDER STEWART, OF MUSKEGON, MICHIGAN, ASSIGNOR TO HILL-INDEPENDENT MFG. CO., OF MUSKEGON, MICHIGAN, A CORPORATION OF ILLINOIS.

SEAL-PRESS.

989,078.

Specification of Letters Patent. Patented Apr. 11, 1911.

Application filed November 25, 1910. Serial No. 594,145.

To all whom it may concern:

Be it known that I, ROBERT ALEXANDER STEWART, a citizen of the United States, and a resident of Muskegon, in the county of 5 Muskegon and State of Michigan, have invented certain new and useful Improvements in Seal-Presses, of which the following is a specification.

This invention relates to improvements in 10 seal presses and it is the object of my invention to provide a press of very simple lines, of exceedingly great strength, and one which is not only unlikely to get out of order but which is as nearly dust proof as it is possible 15 to make one. To this end I employ a main frame having a bifurcated lever pivoted to it and connect this lever to a plunger working within an aperture or, in its preferable embodiment, a through bore and form the 20 plunger with an offset with which co-acts a spring to normally hold said plunger in its upper position; a concealed pivoted latch being also preferably provided to lock the bifurcated handle in its lower position, against 25 the tension of its spring, when desired.

With these objects in view, my invention consists in the seal press as shown in its preferable embodiment in the accompanying drawings and as will be hereinafter described.

Referring to the drawings: Figure 1 is a perspective view of a seal press constructed in accordance with my invention. Fig. 2 is a side elevation of the same, partly in vertical section. Fig. 3 is a perspective detail of several parts. Fig. 4 is a view, similar to Fig. 2, of part of the main frame.

Referring now to the details of the drawings by numerals: 1 designates a U-shaped frame provided with a handle 2 at its rear end and with a seat 4 for the lower die at one extremity of the U and a member 6 at the other extremity of the U having a through bore 8 and a pocket 10 for a spring 40 to be hereinafter described. Within the through bore 8 is slidingly placed a cylindrical plunger 12 which accurately fits the through bore and slides up and down therein with little friction and with absolutely no 45 lateral movement. This cylindrical plunger 12 is provided with an offset 14 which projects over and closes the upper end of the pocket 10 as indicated in Fig. 1. Not only does the offset 14 close the pocket 10, but it 50 also serves its main function of co-acting

with a spring 16 located within the pocket 10, whereby the plunger is normally held in its upper position as shown in Figs. 1 and 2.

To the lower end of the cylindrical plunger 12 I secure the upper die 18, said die 60 having a screw threaded part 20 entering a screw threaded opening within the lower end of the cylindrical plunger 12. The said cylindrical plunger also has two screws 21 and 22 screwed therein from opposite sides and these screws form pivots which pass through the lower ends of a pair of links 24 and 26. The upper ends of these links are pivoted to a simple lever 30, the end of which is bifurcated and straddles the upper part of the 70 member 6, the bifurcated ends 32 and 34 being pivoted to an offset 36, a pivot pin 38 passing through said bifurcated ends and through said offset as clearly illustrated in Fig. 1. The aforesaid links 26 are formed of 75 the shape shown in Fig. 3, and are therefore double and connected together by means of a web 27 which not only serves to connect the double links but also greatly strengthens the links and almost makes them of the 80 strength of a piece of U-shaped channel iron. The lower end of the member 6 of the main frame is provided with slots or openings 39 to permit the pins or pivots 20 and 22 to move partially into the same, as the die 85 moves to its upper position.

In order to form a stop for the movement of the die, the handle 30 is so formed that it contacts with the upper end of the member 1 at the point marked 40 in Fig. 2. 90

In order to lock the parts in position whereby they may be carried in one's pocket or otherwise, I slot the main frame 1 as indicated at 42 and pivot therein a latch 44 on the pivot 46, and the handle 30 is provided with a slot 50 so that when the handle is depressed, the lever will pass down over the latch 44 when the operator may move the latch 44 so that its projection 52 moves over the handle 30 and locks the same in its 100 lower position.

The use of seal presses is so well known that a description of the use of the same is believed to be unnecessary yet, I would point out the fact that my seal press is exceedingly compact, very simple and of the greatest strength.

While I do not limit my invention to a frame having a through bore, it is obvious that there are advantages in the use of such 110

a structure as that shown in the drawings for the reason that the cylindrical plunger 12 accurately fits its through bore and inasmuch as the offset 14 also accurately fits the 5 opening for the spring 16, the cylindrical plunger is not only prevented from any lateral movement which would permit the upper die to get out of registry with the lower die, but also from any movement on 10 the axis of the cylindrical plunger 12.

I am aware that a bifurcated lever has before been proposed and also that a plunger of the kind illustrated is not in itself new, but I believe I am the first one to combine 15 these together and use a simple link connecting the simple lever 30 with the plunger whereby power is transferred from the operating lever 30 in substantially a direct straight line to the plunger supporting the 20 upper die. I deem this of importance.

What I claim as my invention is:

1. In a seal press, the combination of a frame formed of two members, one of said members having openings therein and provided with a fixed handle, a plunger working 25 in one of said openings and having an off-set projecting into the other opening, a spring within the second opening co-acting with said off-set, a bifurcated handle working in co-operative relation with said fixed handle, said bifurcated handle straddling the part of the frame containing the plunger and having its free ends pivoted to said frame at a point to one side of the axis of 30 said plunger, and links on opposite sides of the frame connecting the bifurcated parts of the handle with said plunger, whereby the movement of the pivoted handle toward the fixed handle applies power through said 35 links to said plunger substantially directly in line with the movement of said plunger, substantially as described.

2. In a seal press, the combination of a frame having a plunger working therein and 40 formed with a fixed handle projecting to one side thereof, a die carried by said plunger, and a bifurcated lever pivoted to the frame carrying the plunger and straddling the 45

same and projecting over the fixed handle, said frame having a slot therein located close 50 to that part of the frame containing the plunger and under the part of the pivoted lever which projects over the fixed handle, and a pivoted latch working in said slot and co-acting with the bifurcated handle near 55 the point where it straddles the frame, substantially as described.

3. In a seal press, the combination of a frame formed of two members, one of said members having openings therein and provided with a fixed handle, a plunger working in one of said openings and having an off-set projecting into the other opening, a spring within the second opening co-acting 60 with said off-set, a pivoted bifurcated handle 65 working in co-operative relation with said fixed handle and straddling the part of the frame containing said plunger, and links connecting the bifurcated ends of said pivoted handle with said plunger, each of said 70 links being doubled and connected to its lever on opposite sides of the same, substantially as described.

4. In a seal press, the combination of a frame formed of two members, one of said members having openings therein and provided with a fixed handle, a plunger working in one of said openings and having an off-set projecting into the other opening, a spring within the second opening co-acting 80 with said off-set, a pivoted bifurcated handle working in co-operative relation with said fixed handle and straddling the part of the frame containing said plunger, and links connecting the bifurcated ends of said pivoted handle with said plunger, each of said 85 links being double and formed of one piece of material and having the end of the lever between its doubled parts, substantially as described.

Signed by me at New York city this 21st day of November 1910.

ROBERT ALEXANDER STEWART.
